UNITED STATES PATENT OFFICE.

JESSE G. ZIM, OF MALDEN, MASSACHUSETTS.

GALLEY SIDE-STICK.

1,384,373.

Specification of Letters Patent. Patented July 12, 1921.

Application filed January 28, 1921. Serial No. 440,770.

To all whom it may concern:

Be it known that I, JESSE G. ZIM, a citizen of the United States, residing at Malden, county of Middlesex, Commonwealth of Massachusetts, have invented a certain new and useful Improvement in Galley Side-Sticks, of which the following is a specification, reference being had therein to the accompanying drawings.

- 10 The invention relates to a new and useful improvement in galley side sticks. The object of the invention is to provide a device to be introduced into a galley to extend along the inside face of one of the 15 side walls of the galley to hold in place the lines of type which do not extend the full width of the galley so that the ends of the lines will not fall off.
- The invention comprises substantially two 20 parallel bars secured together by a plurality of springs, each spring being made fast to one of the bars and having a slideable connection with the other bar, whereby the bars are normally held apart by the tension of 25 the springs, the springs yielding to pressure on the bars to permit them to be brought closer together.

The invention will be fully understood from the following description when taken 30 in connection with the accompanying drawings, and the novel features thereof will be pointed out and clearly defined in the claims at the close of this specification.

In the drawings, Figure 1 is a plan view 35 of a galley in which is employed a device embodying the invention shown partly in section.

Fig. 2 is a side elevation, partly broken away, of the locking device shown in Fig. 1. 40 Fig. 3 is a sectional view on an enlarged scale on line 3—3 of Fig. 1.

Referring now to the drawings, there is shown a galley having two side walls 1—2, and containing a plurality of lines of type 45 3 which may be either linotype or lines of type. It is noted that the lines of type do not extend the full width of the galley, that is they are shown as extending to the wall 1 but fall short of the other side wall 2. 50 The side stick is introduced between the wall 2 and the adjacent ends of the several lines of type 3.

The device comprises the two bars 4—5 parallel with each other and yieldingly connected together by springs, so that they may 55 be moved nearer together or farther apart

and always be kept in parallel relation to each other and under tension. These side bars may be made of any suitable material but preferably of wood. On the inner face 60 of the bar 4 there are formed elongated slots 6 which extend longitudinally of the bar.

Thin plates or strips 7 preferably of metal are secured to the inner faces of the two 65 ledges of the bar 4 on the opposite sides of the slot 6, these strips 7 projecting a short distance over the edges of the slot 6 so as to form a relatively narrow entrance to the slot.

A plate spring 8 of bow formation is provided for each pair of slots 6—6, said spring being secured midway of its length to the bar 5. In the drawings, the spring is shown as secured to the bar 5 by means of pins 9. 75 The spring is formed at each end with a neck portion 10 and a head or lug portion 11, the neck 10 being sufficiently narrow for it to pass loosely through the contracted entrance to the slot 6, and the head or lug 11 80 is of greater width than the entrance of the slot. The parts can be assembled by putting the strips 7 in position after the springs 8 are fastened to the bar 5. The head 11 can be inserted through the slot 6 by turning the 85 strip at right angles to bring the thin edge of the lug into alignment with the slot, and bringing the neck 10 into the slot, and then swinging the strip back into place alongside of the slot. The strip is then fastened to the 90 bar by pins. After the parts are assembled and fastened together the head 11 will not pull out of the slot.

The spring is secured to the side bar 5 not only midway of the length of the spring but 95 at a point midway between the two slots 6—6 in the bar 4. The ears 11 are then bent down substantially at right angles to the body of the spring, as shown in Fig. 1.

It will be obvious that if the side bar 5 100 is pressed toward the side bar 4 the springs 8 will be straightened out and the elongated slot 6 will allow for the two opposite lugs 11—11 spreading apart from each other as the spring is elongated by the straightening 105 thereof.

It will thus be seen that if the device is inserted in the galley with the side bar 4 against the side of the galley and the side bar 5 against the ends of the lines of type, 110 the normal tension of the springs 8 will hold the side bar 5 with yielding pressure against

the ends of the lines of type and hold them firmly in position, pressing the opposite ends of the lines of type against the side 1 of the galley by an elastic pressure. If it is 5 desired to have the lines of type a little longer the side bar 5 will yield for such purpose.

What I claim is:—

1. A side stick for type galleys comprising two side bars, a plurality of springs each fixedly secured intermediate its ends to one of the side bars, the other side bar being formed with elongated slots in its inner face, and each of said springs being formed at 15 its opposite ends with lugs which engage with said slots, said lugs being connected with the body of the spring by neck portions, and guard members secured to the

slotted face of the bar which form a narrow entrance to the said slots and form a 20 passageway for the necks of the springs.

2. A side stick for type galleys comprising two parallel bars, a plurality of bow springs each fixedly secured intermediate its ends to one of the side bars, the other side 25 bar being formed with elongated slots in its inner face, said slots having a contracted entrance, each of said springs being formed with portions at its opposite ends which engage with said slots and are movable lengthwise in said slots to allow the unflexing of the springs and permit the said bars to be brought nearer together.

In testimony whereof I affix my signature.

JESSE G. ZIM.
